UNITED STATES PATENT OFFICE..

SOL EINSTEIN, OF CINCINNATI, OHIO, ASSIGNOR, BY MESNE ASSIGNMENTS, TO CINCINNATI GRINDERS INCORPORATED, OF CINCINNATI, OHIO, A CORPORATION OF OHIO.

INTERNAL GRINDER.

Application filed September 16, 1924. Serial No. 738,020.

This invention relates to grinding machines, and more particularly to that type of grinding machines adapted accurately to grind and finish internal cylindrical surfaces.

5 Inasmuch as machines of this nature are used to produce work in which a high degree of accuracy is required, it is essential that the machines operate with great precision and to that end it is necessary that vibration, 10 lost motion, etc. be reduced to a minimum.

Furthermore, as the work must necessarily be inspected and removed frequently, it is desirable that the machine be so constructed that the attendant may perform these operations with the greatest facility and with 15 the least possible loss of time.

This invention therefore has for an object to provide an internal grinding machine which will function with great precision, 20 which may be easily and conveniently operated and in which substantially all of the parts are actuated automatically to produce a complete grinding operation.

A further object of the invention is to 25 provide improved means for effecting relative movement between the work-supporting head and the grinding wheel in transverse directions.

Still another object is to provide, in a machine of this nature, improved means for 30 controlling the back and forth movements of the grinding-wheel support during a grinding operation and mechanical means for retracting the grinding wheel to an out-of-the-way position at any desired time and at the 35 completion of the grinding operation, to give the attendant unobstructed access to the work for the purpose of inspection or removal of the work.

40 A still further object of the invention is to provide automatic means for disconnecting the work-rotating means from its source of power simultaneously with the abnormal movement of the grinding wheel and applying thereto means to overcome the momentum of the work-holder whereby the work is quickly brought to rest.

Another object of the invention is so to 45 construct and coordinate the various trains of mechanism throughout the machine-tool 50 that they may readily be operated with a

minimum amount of power from a single source and to provide simplified and conveniently located controlling means for such trains of mechanism.

55 A further object of the invention is to provide improved means for positively rotating the grinding wheel during its traverse toward and from the work and to provide means for lubricating the normally hidden driving mechanism without discontinuing the operation of the machine.

In machines of this nature there is commonly provided a rotatable work-holder, a rotatable grinding-wheel and means to cause 60 relative bodily movement between the work-holder and the grinding-wheel lengthwise of the axis of the latter, and also relative bodily movement between the two transverse to the axis of the grinding wheel. The first named 65 relative movement is utilized to cause the grinding wheel to enter the cylindrical work and to be fed back and forth therein while the work is rotated. Thus the entire surface to be ground is brought to the action of the 70 grinding wheel.

In the present machine, the relative lateral movement between the work-holder and the grinding-wheel is effected at a relatively 75 slow rate and serves to feed the work to the periphery of the grinding-wheel after each 80 grinding of the work-bore. This continued grinding operation gradually enlarges the bore and when the desired diameter is attained the grinding is discontinued by with- 85 drawing the tool from the work.

In this machine relative bodily movement between the tool and the work, in the direction of the axis of the tool, is preferably effected by mounting the grinding wheel and 90 its rotating mechanism on a table slidably mounted on the base of the machine and providing means for translating the table toward and from the work-head.

The relative lateral movement between the 95 work-head and the tool may conveniently be effected by slidably supporting the work-head in guideways formed in the base transverse to the axis of the grinding wheel and providing a suitable screw-feed for moving 100 the work-head in said guideways. The feed-screw is preferably actuated by the relative

axial movement between the work and grinding-wheel so that a feeding movement is effected upon each reciprocation of the latter.

5 The extent of axial movement of the grinding-wheel is controlled by suitable dogs adjustably carried by the table which, in the movements of the table, actuate a reversing mechanism to change the direction 10 of feed of the table.

It is desirable that the tool-head and the grinding wheel carried thereby be capable of receiving an abnormal movement away from the work to permit the operator to inspect 15 the work and to remove it from the work-holder upon completion of the grinding operation. To this end, means is provided whereby the operator may, at will, render ineffective one normally operative reversing dog whereupon the next retractive movement of the tool-head will continue until an auxiliary dog, also carried by the table, is brought into contact with the feed-reversing lever. At this instance suitable 20 mechanism disconnects the power feed and the table is brought to rest. Immediately upon disconnection of the power feed, a manual feed is rendered effective.

It is, of course, desirable that the grinding 25 operation be effected as rapidly as possible to the end that maximum production be secured. A change-gear device is therefore embodied in the table-feeding mechanism whereby the table and the grinding wheel 30 carried thereby may be translated at the highest rate consistent with the nature of the work being operated upon.

The abnormal movement of the table may 35 be effected at a materially faster rate than is permissible for any grinding operation and therefore there is provided a rapid feed drive which is rendered effective only when the table is to be given its abnormal movement.

40 Inasmuch as in certain classes of work it is necessary that the grinding-wheel be retracted frequently for the purpose of inspection or removal of the work, this rapid table feed, in the aggregate, effects a material saving in time and a proportionate increase in production and is therefore a very important feature of the machine.

45 As before stated the work is held in a work-holder or chuck which also is rotated during the grinding operation. To permit removal of the work, it is necessary that the rotation of the work-holder be discontinued and therefore means is provided for disconnecting the work-holder from the source of power simultaneously with the throwing in of the abnormal feed for the table.

50 This invention also proposes means for automatically overcoming the momentum of the work-holder whereby the work is quickly brought to rest without manual aid by

the operator. This is preferably effected by a suitable brake mechanism located adjacent the change-gears and adapted to be actuated simultaneously with the throwing in of the abnormal feed mechanism.

55 Other objects and advantages will be in part indicated in the following description and in part rendered apparent therefrom in connection with the annexed drawings.

To enable others skilled in the art so fully 60 to apprehend the underlying features hereof that they may embody the same in the various ways contemplated by this invention, drawings depicting a preferred typical construction have been annexed as a part 80 of this disclosure and, in such drawings, like characters of reference denote corresponding parts throughout all the views, of which:—

Fig. 1 is a front elevation of a grinding machine embodying the present invention. 85 Fig. 2 is an enlarged front elevation, partly in section of a portion of Fig. 1 showing particularly the gear-box and the parts associated therewith. Fig. 3 is a plan of Fig. 2. Fig. 4 is a view similar to Fig. 3 but showing in full and dotted lines the mechanism within the gear-box and the table-feeding mechanism, certain other parts being omitted for the sake of clearness. Fig. 5 is a vertical section on lines 5—5 of Figs. 4 and 10. 90 Fig. 6 is a similar view on lines 6—6 of Figs. 4 and 10. Fig. 7 is a vertical section on lines 7—7 of Figs. 4 and 10. Fig. 8 is a horizontal section through the gear-box showing more clearly the shiftable gear-units and the shifting devices therefor. Fig. 9 is a detail sectional view of the controlling means for the table traverse mechanism. Fig. 10 is a sectional development 100 of the gear-mechanisms for effecting the table traverse, for actuating the coolant pump, and for rotating the work-rotating driving shaft all later to be described. Fig. 11 is a horizontal section of the table traverse actuating mechanism together with a 105 load-and-fire device for automatically shifting the gears to change the direction of movement of the table. Fig. 12 is a section through the prime-mover showing the controlling clutch and the means for actuating it. Fig. 13 is a detail section on the line 110 13—13 of Fig. 12. Fig. 14 is a vertical section substantially on the line 14—14 of Figs. 1 and 15. Fig. 15 is a vertical section on the line 15—15 of Fig. 14. Fig. 16 is a detail 115 plan of the means for shifting one of the translatable gear-units and for holding it in its adjusted positions. Fig. 17 is a detail of the gear-shifter illustrated in Fig. 16 showing it engaging the gear-unit to be shifted. Fig. 18 is a vertical section on the line 120 18—18 of Figs. 1 and 19 showing the mechanism for rotating the work-holder and for feeding the work-head transversely of the machine-base. Fig. 19 is a section on the 125 130

line 19—19 of Fig. 18. Fig. 20 is a side elevation of the ratchet and pawl mechanism for effecting the transverse feed of the work-head. Fig. 21 is a horizontal section substantially on the line 21—21 of Fig. 20. Fig. 22 is a diagrammatic view representing the work and four different positions of the grinding wheel.

Referring more particularly to the drawings the invention is disclosed in an internal grinding machine constructed with a base A supporting a closed housing B which carries, in a manner later to be described, a work-head C and a suitable tool-head D. Within the housing B and lengthwise thereof there is journaled a drive-shaft 1 adapted to receive power from a power pulley, or other prime-mover, 2. This drive-shaft is adapted to furnish power for the operation of all of the various trains of mechanism as will later be described. A suitable clutch mechanism indicated generally as 3 (Fig. 12) is interposed between the pulley 2 and the shaft and serves, upon manipulation of a hand-lever 4, to lock the two together to drive the latter from the former. While the specific construction of the clutch mechanism forms no part of the present invention it may nevertheless be stated that it is preferably of the friction type and is adapted to be actuated by the movement of a wedge-bar 5 slidably fitted within a channel in the drive shaft 1. (Figs. 12 and 13.) The hand-lever 4 is secured upon one end of a short shaft 6 journaled in the housing B. To the opposite end of the shaft 6 there is secured an arm 7 having an operative connection with a grooved collar 8 slidably mounted upon the shaft 2 and having a fixed connection with the wedge-bar 5. Thus by manipulation of the hand-lever 4 a driving connection between the pulley 2 and shaft 1 may be effected or broken.

Grinding wheel rotating mechanism.

As hereinbefore stated the grinding wheel is rotated from the drive shaft 1. This drive is effected by mechanism now to be described, particular reference being had to Figs. 1, 14 and 15.

Fixed to one end of the drive-shaft 1 is a pulley 9 connected by means of a belt 10, with a smaller pulley 11 secured upon a counter-shaft 12. This counter-shaft is journaled within the housing B in bearings 13 and 14 and has splined to it, intermediate its ends a driving pulley 15. An idler pulley 16 (shown in dotted lines only, Fig. 1) engages the belt 10 intermediate the pulleys 9 and 11 and serves to maintain the belt taut. The pulley 15 is preferably secured upon a sleeve 17 by means of a key 18 which also tracks a groove 19 formed in the shaft 12 thereby preventing relative rotation be-

tween the shaft, sleeve and pulley yet permitting relative movement thereof lengthwise of the shaft for a purpose later to be explained. The sleeve 17 is journaled in bearings 20 and 21 provided by a hanger 22 fixed to the underside of a translatable table T. This table is slidably mounted on guideways 23 and 24 provided by the housing B and is moved back and forth thereon by means later to be described.

Fixed upon the upper surface of the table T, as by means of screws 25, is the tool-head D within which is journaled a spindle 26, carrying at one end the grinding wheel W and at the opposite end a pulley 27 adapted to be connected by a belt 28 with the pulley 15. The belt 28 is preferably maintained taut by means of an idler pulley 29 rotatably carried by an arm 30 adjustably supported by the hanger 22 coaxial with the shaft 12. This arm may be adjusted about its fulcrum by a screw-threaded shaft 31 having a threaded connection with a pin 32 rotatably carried by the arm. The shaft 31 preferably extends upwardly through the table and is provided with an adjusting wheel 33. Thus through rotation of the wheel 33 the idler pulley 29 may be caused to apply more or less tension to the belt 28.

Table traverse mechanism (slow).

The table T is slidably mounted upon the guideways 23 and 24 and is moved back and forth thereon by mechanism shown more particularly in Figs. 1, 10, 11 and 14.

To the underside of the table there is secured, as by screws 34, a bracket 35 supporting a rack-bar 36. The teeth of this rack-bar are maintained constantly in mesh with a pinion 37 secured upon a shaft 38. This shaft is journaled in a bearing 39 provided by a sub-casing 40 fixed upon the side of the housing B. The shaft 38 may be rotated either manually or by power supplied by the drive shaft 1.

In the normal operation of the machine, power is taken from the drive-shaft through suitable reduction gearing which effects a relatively slow traverse of the table. When the grinding operation is finished, or whenever it is desired to withdraw the tool-head for the purpose of inspecting the work, power is caused to flow through a somewhat different train and thereby causes a relatively rapid traverse of the table. This rapid traverse is also utilized to return the table from its abnormal position to its position wherein the grinding wheel is adjacent the work to be operated on. The relatively slow power feed will now be described.

Upon the shaft 1, there is secured a sprocket-wheel 41 (shown in dotted lines only Fig. 1) which is connected, by means of a suitable chain 42, with a second sprocket-wheel 43 secured upon one end of a short

shaft 44 journaled in bearings 45 carried by a sub-casing 40. (See Fig. 10.) Upon the opposite end of the shaft 44 there is secured a gear 46 which meshes with the teeth 47 of a gear-unit 48 rotatably mounted co-axial with a shaft 49 also journaled in the sub-casing. This gear-unit is also provided at one end with clutch teeth 50 later to be referred to. The teeth 47 constantly engage the teeth 51 of a gear-unit 52 journaled on a bushing 52^x surrounding a shaft 53 rotatably supported by the sub-casing. The gear-unit 52 is also provided at one end with clutch-teeth 54 which, in the slow power drive, engage similar teeth 55 provided by a shiftable unit 56 splined upon the shaft 53. Fixed upon the shaft 53 is a gear-unit 57 formed with gears 58, 59 and 60 adapted to be engaged selectively with gears 58^a, 59^a and 60^a provided by a shiftable gear-unit 61 splined upon the shaft 49. A clutch-member 62 formed with clutch-teeth 63 is fixed to the shaft 49 and is adapted, in the normal slow power drive for the table, to engage similar clutch-teeth 64 provided by a shiftable gear-unit 65 loosely journaled upon the shaft 49. It is to be noted that in Fig. 10 the shiftable units 56, and 61 are shown in neutral positions, which positions, however, they do not occupy during the normal operation of the machine tool. The gear-unit 65 provides a gear 66, which in all of the adjusted positions of the unit, meshes with and drives a gear 67 secured upon a shaft 68 journaled in bearings 69 in the sub-casing 40. Clutch-teeth 65^a, similar to the clutch-teeth 50, are also provided by the gear-unit 65, for a purpose later to be described. Loosely journaled upon the shaft 68 are two bevel gears 70 and 71 both of which mesh constantly with the teeth of a larger bevel-gear 72 loosely journaled on a stub shaft 73 fixed in the sub-casing. These bevel gears 70 and 71 are formed with clutch-elements 70' and 71', respectively, which are adapted alternately to be engaged with clutch teeth 70^x and 71^x provided by a shiftable clutch-member 74 splined to the shaft 68. Thus by shifting the clutch member either of the gear members 70 or 71 may be caused to rotate (in opposite directions) the gear 72 which in turn effect translation of the table in opposite directions. The means for automatically shifting the clutch-member 74 will later be described. Formed integral with the gear 72 is a gear 75 permanently in mesh with a gear 76 forming a part of a gear-unit 77 rotatably journaled on a stud 78 carried by the sub-casing. The gear-unit 77 also provides a gear 79 which meshes with a gear 80 provided by a non-translatable gear-unit 81 rotatably journaled coaxial with the shaft 38. Splined to the shaft 38 as best shown in Figs. 7 and 14 is a clutch member 82 pro-

vided at one end with clutch-teeth 82^a adapted to engage clutch-teeth 81^a formed in the unit 81, thus completing a driving connection from the shaft 1, to the shaft 38, whereby the table is translated to cause the grinding-wheel to approach or recede from the work-holder dependent upon whether the gear 70 or 71 is driving the gear 72.

The gear-unit 61 may be shifted lengthwise of its supporting shaft 49 selectively to connect either the gears 58 and 58^a, 59 and 59^a or 60 and 60^a, thereby to effect translation of the table at any one of three given speeds. Referring particularly to Figs. 1, 4, 5 and 8 there is disclosed the following means for shifting the unit 61. Journaled in a cover-plate 126^a, later to be referred to, is a pin 130 to which is secured at one end a crank 131. The opposite end of the pin carries an arm 132 within which is fixed a crank pin 132^a which tracks a groove 133^b provided in an extension 133^a of a gear-shifter 133. The gear-shifter 133 is slidably mounted on a rod 133^c, secured within a gear box 126 later to be referred to, and carries an arm 133^d which fits within an annular groove 61^c in the unit 61. Thus it will be seen that by shifting the crank 131 to any one of the positions *u* *v* or *w* the shifter 133 and thereby the gear-unit 61 will be shifted laterally and any one of three speeds may be given to the table feed.

Reversing mechanism for table traverse.

As hereinbefore stated the direction of movement of the table T is determined by the position of the clutch-member 74. This member is adapted automatically to be shifted lengthwise of the shaft 68, to cause it to engage either of the sets of clutch-teeth 70' or 71', by means now to be described. (Figs. 1, 2, 3, 6, 11.)

Secured upon a pin 83, journaled in the subcasing 40, is a lever 84 which extends upwardly and is provided at its upper end with a hand-grasp 85. Intermediate the ends of the lever 84 there is formed a laterally projecting boss 86 within which is slidably fitted a retractile plunger 87.

Adjustably secured to the table T are two dogs 88 and 89 of which the former is provided with an abutment 88^x adapted, in the retracting movement of the table, normally to engage the pin 87 thus causing the lever 84 to rock the pin 83 in a clockwise direction as viewed in Fig. 3. The dog 89 is formed with a projection 89^x which, in the forward movement of the table T, engages the boss 86 thus shifting the lever 84 to the left and rocking the shaft 83 in a counter-clockwise direction. The rocking movements of the shaft 83 serve to actuate a load-and-fire mechanism which in turn actuates a suitable clutch-shifting fork 90 engaging the reduced portion 74^b of the clutch-member 74.

Secured upon the shaft 83, within the sub-casing 30, is a downwardly extending arm 91 having its lower end connected with a yoke 92. This yoke is formed with laterally projecting ends 92^a and 92^b adapted to engage, respectively, the peripheral flanges 92^c and 92^d of collars 92^c and 92^d slidably mounted on a rod 93 secured in bosses 93^a provided by a sub-easing cover-plate 40^c. A coil-spring 94 surrounds the rod 93 and normally tends to hold the collars 92^c and 92^d separated. Gravity actuated triggers 95 and 96 are pivoted upon pins 95^a and 96^a carried by the bosses 93^a and are formed with shoulders 95^b and 96^b adapted to engage the peripheral flanges of the collars 92^c and 92^d, respectively. The triggers 95 and 96 are also provided with bevelled ends 95^c and 96^c respectively which, in certain movements of the arm 91, are adapted to be engaged by a pin 97 carried by the arm 91 for a purpose later to be explained.

The clutch-shifting fork 90 is formed integral with a sleeve 90^a slidably mounted on a rod 98 also carried by the bosses 93^a. This sleeve is notched out at 90^b and 90^c to provide walls 90^d and 90^e which are adapted to engage the flanges 92^c and 92^d respectively.

The operation of the clutch shifting mechanism is as follows:

Considering the parts to be in the position shown in Fig. 2 and with the clutch teeth 71^x and 71^y (Fig. 10) in engagement, the table T will be retracting or moving in the direction indicated by the arrow t (Fig. 2). A continued movement of the table in that direction will cause the abutment 88^x to engage the plunger 87 thus causing the lever 84 to be moved to the right and the shaft 83 to be turned clockwise. This movement causes the lower end of the arm 91 and the yoke 92 to be moved to the left as viewed in Fig. 2. Due to the engagement of the yoke 92 with the flange of the collar 92^b the latter member will also be moved to the left against the action of the spring 94 then being compressed against the collar 92^c which latter is prevented from moving under action of the spring by the trigger 95. A still further movement of the arm 91 causes the pin 97 to engage the bevelled end 95^c of the trigger 95 thus lifting the trigger and causing the shoulder 95^b to release the flange 92^c. Immediately upon its release the collar 92^c is moved to the left by the power stored in the spring 94 and, due to the engagement of the flange 92^c with the wall 90^c, the sleeve 90^a and its attached shift-fork 90 are also moved to the left thus shifting the clutch-member 74 into engagement with the clutch teeth 70^x and thereby reversing the direction of the table feed.

It will be understood that in the forward movement of the table the projection 89^x, boss 86, arms 84 and 91, pin 97, lever 96,

collar 92^d etc. will act in the manner just previously described, to again reverse the direction of table traverse.

The hand grasp 85 provides means whereby the operator may either stop the translation of the table or reverse its movement at will.

Abnormal table traverse.

Inasmuch as the work being operated on requires frequent inspection and removal from its carrier and also as it is not practical to stop the rotation of the grinding wheel during such inspection and removal, it has been found desirable to provide means whereby the table and the grinding wheel carried thereby may quickly be moved to an abnormal position wherein it will not interfere with or endanger the operator. Means for effecting this abnormal movement is now to be described.

Supposing that the operator desires to inspect or remove the work from the work-carrier, the first thing that he does is to withdraw the pin 87 out of the path of the abutment 88^x. Upon the next retracting movement of the table T, instead of the abutment 88^x shifting the lever 84 and thus reversing the table feed, it will pass idly by the lever and continue to move to the right, as viewed in Figs. 2 and 3. This movement will continue until an abutment 100^a, provided by a dog 100 adjustably secured to the table T, engages the boss 86 and shifts the lever 84 as previously described, which disconnects the clutch-teeth 71^x and 71^y and engages the teeth 70^x and 71^y. Simultaneously with the shifting of the lever 84, a cam 100^b carried by the dog 100 engages the free end of an arm 101 secured upon an upright feed-controlling shaft 102 and shifts said arm to its dotted line position shown in Fig. 3. Fixed to the shaft 102, in a manner later to be described, is a clutch-shifting fork 103 which engages the clutch-member 82 and, as the arm 101 and shaft 102 are rotated counter-clockwise as viewed in Fig. 3, this fork shifts the clutch-member 82 and disconnects the clutch-teeth 81^a and 82^a thereby breaking the driving connection between the gear-unit 81 and the shaft 88 and bringing the table to rest in its extreme retracted position. A further rotation of the shaft 102 causes the clutch-member 82 to be moved toward the front of the machine until the clutch-teeth 82^b thereof engage similar clutch-teeth 104^t provided by a short shaft 105 journaled in the cover-plate 40^c. A hand-wheel 105^a also secured to the shaft 105 affords means for manually rotating shaft 88 and thereby moving the table T toward or from the work-holder.

The table is brought to rest at the end of its abnormal movement with the arm 101 in contact with the cam 100^b, therefore when

it is desired to again start the table feed, which can only be effected by shifting the clutch teeth 81^a and 82^a into engagement it is necessary that the yoke 103 be shifted 25 while the arm 101 is held against movement. This is preferably effected by means of a detachable connection between the arm 101 and the fork 103. Loosely journaled on the shaft 102 is a sleeve 104 having a tongue-10 and-groove connection 104^a with the fork 103. This sleeve also carries a pivoted lever 105^b which affords means for oscillating the sleeve 104 and thereby moving the fork to shift the clutch-member 82. The lever 105^b 15 is provided with an arm 105^a adapted, in a certain position of the lever and shaft 102, to engage a slot 106^a formed in a collar 106 secured upon the lower end of the shaft 102. A spring plunger 107 carried by the 20 collar 106 acts upon cam-surfaces 107^a provided by the sleeve 104 and tends to position the collar 106 so that the arm 105^a will normally rest in the slot 106^a which insures that the fork 103 will be actuated whenever the cam 25 100^b shifts the arm 101, as hereinbefore described.

By lifting the lever 105^b the arm 105^a will be withdrawn from the slot 106^a and the fork 103 may be oscillated independently of 30 the arm 101. A second spring-pressed plunger 108 slidably mounted in the sub-casing 40 (see Fig. 7) is adapted to contact with opposite faces of a pin 108^a carried by the sleeve 104 to hold the shiftable clutch-35 member 82 in either of its operative positions.

Rapid table traverse during abnormal movement.

40 To reduce to a minimum the time required to give the table its abnormal movements there is provided a rapid feed which is automatically thrown into action when the table begins its abnormal movement and 45 which is automatically thrown out when the table has been returned to its normal position with the grinding wheel adjacent to the work. Referring more particularly to Figs. 2, 3, 5, 6 and 10, this rapid feed is effected 50 by shifting the gear-unit 65 to the left (Fig. 10) thereby disconnecting the clutch teeth 63 and 64 and engaging the clutch teeth 50 and 65^a hereinbefore referred to. From an inspection of Fig. 10, it will be observed that 55 with the gear member 65 connected directly to the gear 48 the gear 67 will be driven at a materially faster rate than when power is flowing through the elements 52, 56, 57, 61, 62 etc. as previously described.

60 It will also be obvious that inasmuch as it is necessary to give the table its abnormal movement very frequently this rapid feed will, in the aggregate, effect a great saving in time and likewise proportionately increase the production of the machine.

65

The gear-unit 65 is preferably shifted lengthwise of the shaft 49 by mechanism now to be described. Journaled within the sub-casing 40 is a vertically disposed shaft 109 carrying at its upper end a cross-head 110 which has secured to it, at its opposite ends, studs or rollers 111 and 112. This cross-head, during the grinding operation, occupies the full-line position shown in Fig. 3.

The lower end of the shaft 109 carries a segmental lever 113 (Figs. 2, 6, 16 and 17) which is connected by a link 114 to a crank arm 115 fixed to a vertical shaft 116 journaled in the sub-casing 40. Secured to the shaft 116, adjacent its lower end, is a two-armed lever 117 comprising arms 117^a and 117^b of which the former carries a block or roller 118 fitted within the annular groove 65^a of the unit 65. From the foregoing, it will be seen that oscillation of the shaft 109 will, through the connection described, result in translation of the gear-unit 65.

The dog 88 carried by the table T is provided with a cam-surface 111^a which, as the abutment passes the lever 84 at the beginning of the abnormal table feed, engages the stud 111 thereby forcing outwardly on the stud and oscillating the cross-head and shaft 109 clockwise (Fig. 3) to the dotted line position. This oscillation throws in the rapid feed as previously described. A spring-pressed detent 119 (Fig. 16) then engages a notch 113^a in the segmental arm 113 and retains the parts in their adjusted positions until, upon a forward movement of the table, a cam-surface 112^a also provided by the dog 88, engages the stud 112 again shifting the cross-head 110 to its full line position Fig. 3 thereby throwing out the rapid feed and restoring the slow power-feed for the table. In this latter position the detent 119 engages the notch 113^b in the arm 113 and prevents accidental movement of the parts.

Work rotating mechanism.

As hereinbefore stated the work is preferably rotated during the grinding operation and to that end it is held in a suitable chuck or work-holder H carried by a spindle S rotatably journaled in bearings b and b' provided in the work-head C. The spindle S carries a pulley 120 which is connected by means of a belt 121, with a driving pulley 122 secured upon one end of a shaft 123 journaled lengthwise of the machine within the housing B. The opposite end of the shaft carries a splined gear-unit 124 formed with gears 58^a, 59^b and 60^b adapted selectively to be meshed with the gears 58, 59 and 60 respectively. The gear-unit 124 may be shifted to any one of its three operative positions by means of a crank 125 fixed upon a pin 125^a. This pin is rotatably journaled

in a cover plate 126^a of a gear-box 126 forming a part of the sub-casing 40 secured to the housing B as by screws 126^b. The pin 125^a also carries (substantially at right angles to 5 crank 125) an arm 127 provided with a pin 127^a fitted within a groove 128^a provided by an extension 128^b a bodily movable gear-shifting fork 128 slidably mounted on the shaft 68. This gear shifting fork engages 10 the gear-unit 124 (see Fig. 8) and by manually shifting the crank 125 to x y or z the gears 58 and 58^b, 59 and 59^b or 60 and 60^b may selectively be engaged to give the work-holder any one of three speeds of rotation. 15 Intermediate the pulleys 120 and 123 the belt 121 passes between belt-guiding pulleys 121^a and 121^b rotatably journaled in a bearing bracket 121^c fixed to the underside of a work-head supporting-table 140. The belt 20 121 is preferably held taut by means of an automatically acting belt tightener comprising a pulley 121^d journaled in one arm of a bell-crank lever 121^e fulcrumed at 121^f in the housing B. The other arm of the lever 25 121^e carries a weight 121^g which tends to swing the lever 121^e about its fulcrum and thereby holds the belt taut.

Brake for work rotating mechanism.

30 As hereinbefore stated, it is necessary in the operation of grinding machines frequently to withdraw the grinding wheel from the work to permit inspection, removal and replacement of the latter. In the present machine in order that the time required for this withdrawal may be reduced to a minimum, there is provided a rapid-feed which is adapted to be brought into action at any desired time. 35 To further reduce the time required to inspect or remove the work this invention provides novel means for positively and automatically arresting the rotation of the work-carrier simultaneously with the throwing in of the rapid table feed to withdraw 40 the grinding wheel from the work.

As shown more particularly in Figs. 4, 50 8 and 10, this means comprises a friction brake consisting of a cone 56^a forming a part of the unit 56 splined upon the shaft 53. This cone is adapted at certain times to contact with a braking face 56^b of a friction element 56^c fixed within a bracket 56^d formed integral with the subcasing 40.

55 The shiftable unit 56 is operatively connected with the arm 117^b of the lever 117 and therefore oscillation of the shaft 116 to throw in the rapid feed for the table will simultaneously force the cone 56^a into contact with the braking face 56^b thereby arrest 60 the rotation of the shaft 53 which in turn causes the work-head to be brought to rest.

Work-head translating mechanism.

65 The work-head C is adjustably mounted

on a table 140 provided at its opposite edges with undercut guides 140^a and 140^b. These guides slide within guideways 141^a and 141^b provided by a supplemental base 141 fixed upon the housing B.

70 During the grinding operation the table 140 is moved transverse to the axis of the grinding wheel to gradually feed the work carried by the work-head to the grinding face of the grinding-wheel. This feeding 75 movement is effected by means of a screw 142 (Fig. 18) rotatably journaled in the supplemental base 141, which screw has a threaded connection with a nut 143 secured to the underside of the table 140.

80 The screw is preferably rotated step-by-step in time with reciprocations of the table T and the grinding-wheel. To this end there is secured to one end of the screw a gear 144 permanently in mesh with a pinion 145 secured upon the reduced end of a shaft 146. Rotatably mounted, coaxial with the shaft 146 is a wheel 147 provided with ratchet teeth 148. These teeth are engaged by a pawl 149 carried by an oscillating arm 150 also journaled coaxial with the shaft 146. Oscillatory movements are given to the arm 150 by a link 151 pivoted at one end to the arm and adjustably connected at its other end to a vibrating lever 152 pivoted at 153 in the base 141. The lever 152 receives its motion from a link 154 connecting the lever 152 with the feed-controlling lever 85 84. Thus upon each movement of the lever 84 to start the forward table-feed the 100 link 154, lever 152, link 151, arm 150, pawl 149 and ratchet 148 operate to slightly rotate the feed-screw and thereby shift the work-head laterally.

85 An indexing mechanism is also provided 105 for the feed just described. This mechanism comprises a manually rotatable disk 155 carrying a retractible spring-plunger 156 adapted to be inserted into any one of the holes 157 in the wheel 147. The disk 110 155 is secured to a stub shaft 158 which also carries a pinion 159 meshing with a gear 160 journaled in the hub of the wheel 147. The gear 160 is formed integral with a pinion 161 which meshes with a gear 162 fixed 115 to the shaft 146. Thus rotation of the disk 155 for the insertion of the plunger 156 into any one of the holes 157 will produce a partial rotation of the feed-screw 142 for a purpose well understood by those skilled in the 120 art.

Lubricating device for grinding wheel rotating mechanism.

125 The driving mechanism for the grinding wheel is wholly enclosed within the housing B and inasmuch as the pulleys 15 and 29 are rotating continuously, the sleeve is being moved back and forth on the shaft 12, and the pulleys 29 is adjustable to various 130

positions about the axis of the shaft 12, proper lubrication of the parts is quite a problem. This problem has been solved, however, very effectively by an exceedingly simple and novel manner.

Within the table T, and wholly covered by the tool-head D, there is formed an oil reservoir R adapted to be filled in any suitable way, as for example, through a port p in the tool head. Oil tubes o and o' connect the reservoir with the bearings 20 and 21 and generously lubricate them in all of their adjusted positions lengthwise of the shaft 12. The pulley 29 is carried by the swinging arm 30 and therefore has a bodily movement relatively to the reservoir which precludes the connection of a substantially rigid tube from that reservoir R to the bearing 29. Lubrication of this bearing is effected however, by providing the arm 30 with a trough-like member 30^x having an oil delivery duct 30^y extending into the bearing for the pulley 29. The trough 30^x is made of a length greater than the normal movement of the pulley 29 and an oil tube o" connected to the reservoir R terminates slightly above the trough and conveys oil thereinto in all of the adjusted positions of the arm 30. By this means the normally hidden and inaccessible continuously shifting parts are generously and conveniently lubricated.

Coolant transmission.

To prevent heating of the work, means is provided for supplying a coolant thereto continuously during the grinding operation. This means is so combined with the work rotating means that the flow of cool air is started automatically when rotation of the work is begun and stopped automatically when the work is brought to rest.

At the rear side of the machine there is provided a coolant tank L within which operates a pump P adapted upon rotation to force coolant from the tank through a flexible conductor M to a pipe N extending through the spindle S and terminating in a nozzle N'. Any suitable means may be employed for returning the coolant to the supply tank after it has been applied to the work.

The pump is preferably driven by a shaft 170 which carries at its upper end a pulley 171 operatively connected by a belt 172 with a driving pulley 173 rotatably journaled coaxial with the shaft 123. Power to rotate the pulley 173 is supplied by the shaft 53 through a gear 174 fixed to the shaft 53 and a pinion 175 operatively connected with the pulley.

From the foregoing, it will be seen that whenever the work-head is rotated through elements 1, 41, 42, 43, 44, 46, 48, 52, 56, 53 etc. as hereinbefore described, the pulley

173 will also be rotated and coolant will be supplied to the work, but when the unit 56 is disengaged from the gear-unit 52 the shaft 53 is brought to rest and the flow of coolant to the work is discontinued.

It is to be noted that the work-rotating mechanism, the coolant transmission, the slow and rapid table traverse, the brake mechanism and the feed reversing mechanism (in one direction of movement) are all controlled by a single element (88) carried by the table and therefore by a single adjustment the operator may change the time of operation of these mechanisms without disturbing their relation.

The feed-reversing mechanism and the automatic feed throw-out are also controlled by a single element (100) at the end of the abnormal feed and therefore the time of operation of these mechanisms may be changed simultaneously by a single adjustment.

Operation.

Supposing that it is desired to grind a piece of work Z such as is illustrated in Fig. 22 and that the dogs 88 and 89 have been set to such positions that the table will have a back and forth movement sufficient to move the grinding wheel W between the positions w¹ and w² (see Fig. 22) and the dog 100 has been set to function when the grinding-wheel has reached its position w⁴. Now considering that the slow table traverse is operative, the work-head is being moved laterally; the grinding wheel and the work are being rotated, and the pump is supplying coolant to the work, the cycle of operation is as follows:

When the operator desires to gauge or remove the work he retracts the pin 87 out of the path of the abutment 88^x, then upon the next retraction of the table the reversing lever is not actuated by the abutment and the table continues to move away from the work. As the grinding-wheel reaches the position indicated by w³ the cam 111^a on the dog 88 engages the stud 11 thereby shifting the cross-head 110 to its dotted line position in Fig. 3 and oscillating the shaft 109. Oscillation of the shaft 109 effects disengagement of the slow table traverse, engagement of the rapid table traverse, disengagement of the work rotating mechanism, applies the brake to overcome the momentum of the work-head and stops the action of the coolant pump. The table then moves under the action of the rapid traverse and brings the cam 100^b into engagement with the arm 101 which oscillates the shaft 102 and thereby shifts the clutch-member 82 to discontinue the power feed. As the cam 100^b is acting on the lever 101 the abutment 100^a is shifting the lever 84 to move the pin 97 into engagement with the cam 95^c of the trigger 95. (See Fig. 2.) Upon disconnec-

tion of the power feed the table continues to move slightly due to momentum and this final movement is sufficient to cause the abutment 100^a to trip the load-and-fire mechanism and connect the forward feed. If, for any reason, the table does not move sufficiently under momentum to trip the feed reverser, upon the throwing in of the power feed the table will be retracted slightly to cause the abutment 100^a to trip the load-and-fire mechanism, whereupon the table will be fed toward the work. The work now having been brought to rest and the grinding wheel retracted the operator may inspect or remove the work and replace it with a new piece.

To start a new grinding operation the operator slightly raises and turns the lever 105^b to connect the power feed for the table. The table then moves toward the work under the action of the rapid traverse until the grinding wheel reaches the position w^a. At this point the cam 112^a engages the stud 112 and thereby shifts the cross-head from its dotted line position in Fig. 3 to its full line position. This movement oscillates the shaft 109 which in turn disconnects the rapid traverse, connects the slow power feed, releases the brake, starts the work rotating mechanism and starts the coolant pump. The grinding of the new piece then takes place as hereinbefore described.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A grinding machine combining a work-holder; means for rotating said work-holder; a grinding-wheel; means for giving said grinding-wheel movements of predetermined length toward and from said work-holder; means permitting said grinding-wheel to be moved to an abnormal position; and automatically actuated means rendered operative at the beginning of said abnormal movement to arrest the rotation of said work-holder.

2. A grinding machine combining a work-holder; means for rotating said work-holder; a grinding wheel adapted to operate on work held in said work-holder; means for moving said grinding-wheel a prede-

termined distance at a slow rate during the grinding operation; auxiliary translating means for moving said grinding wheel away from said work at a rapid rate; and means operative upon the connection of said rapid translating means of said grinding-wheel for arresting the rotation of said work-holder.

3. A machine-tool combining a work-holder; means for rotating said work-holder; a tool holder; means for effecting relative bodily movement between said work-holder and tool-holder; and means operative upon a predetermined relative movement between said work-holder and tool holder for automatically rendering ineffective said work-holder rotating means without discontinuing the relative bodily movement between said work-holder and said tool-holder.

4. A machine-tool combining a work-holder; means for rotating said work-holder; a tool-holder; means for moving said tool-holder toward and from said work-holder; means actuated by a movement of said tool-holder for rendering ineffective said work-holder rotating means; and means for giving said tool holder an abnormal movement at an increased rate after said work-holder rotating means is rendered ineffective.

5. A machine-tool combining a work-holder; means for rotating said work-holder; a tool-holder; means for effecting relative bodily movement between said work-holder and tool-holder axially of the work, successively at two different speeds; means operative upon the change from one of said speeds to the other for automatically rendering ineffective said work-holder rotating means; and means operative simultaneously with said last named means for overcoming the momentum of said work-holder.

6. A grinding machine combining a work-holder; a drive shaft; a driving connection between said drive-shaft and said work-holder for rotating the latter, said driving connection including a combined clutch-and-brake unit; a stationary friction surface adapted to cooperate with said brake unit; and means for shifting said combined clutch-and-brake unit to break the driving connection for said work-holder and thereafter bringing said unit into contact with said stationary friction surface to overcome the momentum of said work-holder.

7. A grinding machine combining a work-holder; a grinding-wheel; means for moving said grinding-wheel a predetermined distance toward and from said work-holder at a predetermined speed; automatic means for giving said grinding-wheel an abnormal movement at a materially different speed and means whereby said grinding wheel is automatically arrested against translation at the end of said abnormal movement.

8. A grinding machine combining a work-

holder; a grinding wheel; a translatable table upon which said grinding wheel is supported; means for giving said table movements of predetermined amplitude toward and from said work-holder at a predetermined speed; means permitting said table to be given an abnormal movement away from said work-holder, and means operative at the beginning of the abnormal movement to materially increase the speed of movement of the table.

9. A grinding machine combining a work-holder; means for rotating said work-holder; a grinding wheel; a translatable table on which said grinding-wheel is supported; means for giving said table movements of predetermined amplitude toward and from said work-holder at a predetermined speed; means for giving said table an abnormal movement away from said work-holder; and means actuated by said table at the beginning of its abnormal movement to materially increase the speed of movement and simultaneously therewith to discontinue the rotation of said work-holder.

10. A grinding machine combining a work-holder; means for rotating said work-holder; a grinding-wheel; a translatable table on which said grinding-wheel is supported; means for giving said table movements of predetermined amplitude toward and from said work-holder at a predetermined speed; means for giving said table an abnormal movement away from said work-holder; a brake for overcoming momentum of said work-holder, and a single device actuated by said table at the beginning of its abnormal movement to throw in a rapid feed for said table, to disconnect said work-head rotating means and to actuate said brake to arrest the rotation of said work-head.

11. In a grinding-machine; a translatable table; power means for feeding said table in opposite directions; means for controlling the direction of movement of said table; devices carried by said table to actuate said direction controlling means to reverse the direction of movement of the table; and means for rendering one of said devices ineffective to actuate said direction controlling means, whereby said table is given an abnormal movement by said power feed.

12. In a grinding machine; a translatable table; means for feeding said table in opposite directions; means for controlling the direction of movement of said table; devices carried by said table to actuate said direction controlling means to reverse the direction of movement of the table; means for rendering one of said devices ineffective to actuate said direction controlling means, whereby said table is given an abnormal movement; and auxiliary means for bringing the table to rest at the end of its abnormal movement.

13. In a grinding machine; a translatable table; means for feeding said table in opposite directions; means for controlling the direction of movement of said table; devices carried by said table to actuate said direction controlling means to reverse the direction of movement of the table; auxiliary means carried by the table and adapted after said device has been rendered ineffective to actuate said feed reversing means; and means to render said table feed ineffective.

14. In a machine-tool, in combination, a bodily movable member; power means for moving said member back and forth a predetermined distance at a predetermined speed; power means for increasing the movement of said member in one direction and at a materially different speed and control means for selectively causing said increased movement and speed.

15. In a grinding-machine, in combination, a translatable table; a power shaft; means actuated by said power-shaft for translating said table in a single direction at a plurality of speed, said means including a shiftable driving gear-unit, a driven gear permanently in mesh with the gear on said shiftable unit, driving means at opposite sides of said shiftable unit to rotate it at unequal speeds, and means for shifting said gear-unit into engagement with either of said driving means.

16. In a grinding machine, in combination, a translatable member; means for translating said member at a predetermined speed; means for changing the speed of translation of said member; means for changing the direction of translation of said member, said speed-changing means and direction changing means each comprising a pair of opposed driving elements, a shiftable clutch element between said pairs of driving elements, and means actuated by the movement of said translatable member for shifting said clutch elements to cause them alternately to engage its driving elements.

17. In a grinding machine, in combination, a translatable table; translating mechanism for said table including a speed-change device for determining the speed of translation of said table, and reversing means for changing the direction of translation; manually actuated means for adjusting said speed change device; a normally ineffective rapid power feed for said table independent of said speed-change device; dogs carried by said table for actuating said reversing means; means for rendering one of said dogs ineffective; and means acting thereafter automatically to render effective said rapid power feed.

18. A grinding machine combining a translatable table; means for translating said table at any one of a plurality of relatively slow speeds; a second means operat-

ing independently of said first means for giving said table an abnormal feed at a speed materially greater than any of said slow speeds, said last named means comprising a normally slow running gear member; an operative connection between said gear member and said table; a high speed driver for said gear member; and means for shifting said gear member into operative relation 10 with said high speed driver.

19. A grinding machine combining a translatable table; means for translating said table at any one of a plurality of relatively slow speeds; a second means operating independently of said first means for giving said table an abnormal feed at a speed materially greater than any of said slow speeds, said last named means comprising a normally slow running gear member, an operative connection between said gear member and said table; automatically actuated means for discontinuing said slow drive and for shifting said gear member into driving relation with said high speed 20 driver, said last named means comprising a rock shaft, an operative connection between said rock shaft and said gear-member, an arm on said rock shaft, and means carried by said table adapted to engage said arm to 25 oscillate said rock shaft.

20. In a grinding machine, in combination, a table; means for translating said table between two extreme positions, said means comprising two alternately operative 30 feeding mechanisms each adapted to move said table through a portion of its extreme translation, and means for discontinuing one of said feeding mechanisms and simultaneously therewith rendering said other 35 feeding mechanism operative to continue the movement of said table effected by said one of said feeding mechanisms.

21. In a grinding machine, in combination, a translatable table, two feeding mechanisms for translating said table at substantially unequal speeds in a single direction; means alternately rendering said feeding 40 mechanisms operative; and an automatic feed throw-out operative at one extreme position of said table.

22. In a grinding machine, in combination, a translatable table; two alternately operative feeding mechanisms for translating said table in a single direction; and a single control for both of said feeding 45 mechanisms.

23. A grinding machine combining a translatable table; means for translating said table; a work-head; means for rotating said work-head; a power shaft; operative connections between said power shaft and said work-head rotating means and table translating means including a driving gear unit provided with a plurality of gears of varying size; a shiftable gear-unit provid-

ing gears adapted selectively to be meshed with the gears of said first named gear unit to translate the table at varying speeds, a second shiftable gear-unit providing gears adapted selectively to be meshed with said first named gear unit to rotate said work-head at varying speeds; and means for shifting said shiftable gear units.

24. A grinding machine combining a housing; a rotatable work-holder supported by said housing; a table translatable mounted on said housing; a grinding wheel carried by said table; a power shaft journaled in said housing; a sub-casing carried by said housing, a plurality of change-gear mechanisms located within said sub-casing, a single driving gear-unit common to both of said change-gear mechanisms; an operative connection between said power shaft and said driving gear-unit; a table feeding mechanism actuated by one of said change gear mechanisms; and a work-rotating mechanism actuated by the other of said change-gear mechanism.

25. A grinding machine combining a housing; a table translatable mounted on said housing; a spindle rotatably carried by said table; means for translating said table; a power shaft journaled in said housing; a counter shaft rotatably journaled in said housing; an operative connection between said shafts; a bearing-bracket carried by said translatable table; a driving pulley rotatably journaled in said bracket and having a splined connection with said counter shaft; a pulley carried by said spindle and an operative connection between said pulleys.

26. A grinding machine, combining a work-head; means for rotating the work-head; a controlling device for said rotating means; a tool-head; means for translating the tool-head; a reversing mechanism for changing the direction of translation of the tool-head; and a single adjustable element adapted to actuate the work-rotating controlling device and the feed-reversing mechanism.

27. In a grinding machine, in combination, a work-head; means for rotating the work-head; a tool-head; slow and rapid feeds for translating said tool-head; a brake mechanism for overcoming momentum of the work-head when its rotating means is rendered ineffective and a single automatically acting controlling element for all of said mechanisms.

28. In a grinding machine, in combination a work-head mechanism for rotating the work-head; a table; two translating mechanisms for said table; a brake mechanism for overcoming momentum of the work-head when its rotating mechanism is rendered ineffective; mechanism for supplying coolant to the work during the grinding operation; a reversing mechanism for the table trans-

lating mechanism; and a single dog adjustably secured to the table and having a plurality of effective portions for controlling all of said mechanisms.

29. In a grinding machine, in combination, a work-head; means for rotating the work-head; means for supplying a coolant to the work, said means including a pump; an operative connection between the pump and the work-head rotating means whereby the former is actuated by the latter; a grinding tool; means for withdrawing the grinding tool from the work; and automatically acting means operative upon the initial movement of withdrawal of the tool for simultaneously arresting the rotation of the work-head and rendering said coolant pump ineffective.

30. A grinding machine including a rotatable work-holder; means for supplying a coolant thereto; a grinding element reciprocable relative to said work-holder; means for feeding said grinding element at slow and fast speeds; automatic means for shifting from the slow to the fast speed; and control devices operable by said automatic means for stopping the rotation of the work-holder and the flow of coolant thereto as the slow feed is rendered ineffective.

31. A grinding machine including a rotatable work-holder; means for supplying coolant thereto; a grinding element reciprocable relative to said work-holder; power

means for feeding said grinding element at slow and fast speeds; automatic means for shifting from said fast to said slow feeds; and control devices operable by said automatic means for starting the rotation of the work-holder and the flow of coolant thereto simultaneously with engagement of said slow feed.

32. A grinding machine combining a grinding wheel; a grinding wheel support; means for translating said support, said means including a shiftable controlling element; a reversing mechanism for changing the direction of translation of the grinding wheel support; and a single element adapted at one extreme movement of the support to actuate said reversing mechanism and shift said shiftable element.

33. A grinding machine combining a work-head; a grinding wheel; a grinding wheel support; means for moving said support a predetermined distance toward and from said work-head; a reversing mechanism for changing the direction of movement of said support; means permitting said support to be given an abnormal movement; and a single element operable upon said abnormal movement, to actuate said reversing mechanism and render said translating mechanism ineffective.

In witness whereof, I hereunto subscribe my name.

SOL EINSTEIN.
